JOHN PRINGLE MACKIE, OF BELFAST, IRELAND, ASSIGNOR TO JAMES MACKIE AND SONS LIMITED, OF ALBERT FOUNDRY, BELFAST, IRELAND, A BRITISH COMPANY

DELIVERY OF SLIVERS FROM TEXTILE MACHINES INTO CANS

Application filed February 27, 1929, Serial No. 342,969, and in Great Britain May 18, 1928.

This invention relates to the delivery of slivers from textile machines into cans. Many attempts have been made to carry out such delivery so that the sliver is packed in a regular manner in the can, for if that is not arranged, the can is not properly filled and the subsequent unfolding of the sliver, in order to carry out further operations upon it, is rendered difficult. It is the principal

object of the present invention to provide a mechanism for piling sliver into cans in a zigzag manner which would be relatively simple and more satisfactory than devices hitherto employed.

According to the present invention, the sliver is delivered to a pair of rollers turning inwardly with respect to each other about their parallel axes substantially at right angles to the width of the sliver but at a linear speed somewhat less than that at which the sliver is supplied to the rollers. The gap between the surfaces of the two rollers is rather less than the width of the sliver, and these surfaces engage the edges of the sliver, which is delivered to them near the rear end thereof somewhat obliquely. The result of the difference of peripheral speeds is that the sliver is retarded and tends to bulge upwardly and forwardly in an arched form. At the same time the sliver passing between the rollers travels forwards. Before it reaches the front end of the rollers this arch collapses under its own weight and lies along nearly the whole length of the rollers. This section of sliver

passes almost at once between the rollers and the initial conditions are repeated. Thus the sliver is repeatedly folded on itself and therefore enters the can in zig-zag form. The can is reciprocated transversely to the width of the sliver so that the zig-zags are drawn out sideways and occupy the full width of the can.

The two rollers referred to are preferably placed just above the mouth of the can and may be associated with two or more additional rollers so that all the rollers act as presser rollers when the can becomes filled, to roll down the sliver and pack it into the can in a satisfactory manner. In order to enable a can to be removed and replaced by an empty can when full, the sliver may be supplied over

an inclined delivery plate, and at the instant a full can is removed, it may be nipped and held back by a cover or hood which is caused to descend on to the delivery plate at that moment.

A form of construction of a sliver delivery arrangement in accordance with the invention is illustrated in the accompanying drawings, wherein:—

Figure 1 is a side elevation of the delivery end of a carding engine to which the improved arrangement is applied.

Figure 2 is a sectional elevation at right angles to Figure 1 of the upper part of the mechanism taken on the line II—II in Figure 1.

As shown in the drawings, the sliver is being fed into a can *a* carried on a platform *b*, and a can *c* is empty and is waiting to take the place of the can *a* when the latter is full. During the filling, the platform *b* and the cans are reciprocated by means of a crank *d*, connecting rod *e*, and an upstanding bracket *f* carried by the platform *b* to which the connecting rod *e* is attached.

The carding engine is provided with the usual pair of delivery rollers *g*¹, *g*², and an inclined delivery plate *h* is mounted in front of the roller *g*² in such a way that the sliver has to pass over the plate *h* on its way to the can *a*. The cans *a* and *c* are substantially elliptical in plan, and as can be seen, are reciprocated in the direction of the major axes of the cans.

Between the lower end of the delivery plate *h* and the top of the can *a* there are mounted two rollers *k*¹ and *k*² with their axes at right angles to the width of the sliver, and consequently at right angles to the major axis of the can *a*. The rollers *k*¹, *k*² are driven from a spindle *l* through bevel wheels *m*¹ and *m*² so as to turn inwardly as shown by the arrows in Figure 1. In other words, the roller *k*¹ turns clockwise and the roller *k*² counter-clockwise, but at speeds such that the linear speed of the surfaces of the rollers is rather less than that of the delivery rollers *g*¹, *g*² of the carding engine. Furthermore, the width of the gap between the rollers *k*¹ and *k*², as seen in Figure 1, is rather less than the

width of the sliver shown diagrammatically at n . The rollers k' , k^2 , engage the edges of the sliver, which initially is fed to the rear ends thereof down the inclined plate h . The 5 effect of the retardation due to the slower peripheral speed of the rollers k' , k^2 will be clear from Figure 2. The line w indicates the form which the sliver first takes on entering these rollers. Owing to the retardation the 10 sliver by degrees takes the form indicated by the lines x and z , bulging upwardly and forwardly and at the same time travelling forward between the rollers. When it reaches the position indicated at z , its weight 15 causes it to collapse to the position shown by the dotted line y . Thus the sliver is folded back upon itself. That part of it which is adjacent the plate h presently assumes the position indicated at w so that the initial conditions are renewed and the same cycle of 20 operations is repeated. Thus the sliver has imparted to it a more or less regular zig-zag form solely by reason of the retardation aforesaid.

25 After passing through the rollers k' , k^2 the legs of the zig-zag tend to fall apart again owing to gravity. The distance through which it falls is, however, so small that substantially no opening out of the zig-zags takes 30 place, particularly as this form is rendered more or less permanent by the lateral pressure exerted by the rollers. Further, the folds lay themselves flat together as soon as they reach the bottom of the can or the fold previously 35 laid.

30 The velocity ratio between the rollers g' , g^2 and k' , k^2 can be varied within wide limits, depending on the character of the sliver. It may for example be 3:2. Owing to the reciprocation of the can the successive folds are drawn out sideways so that the whole width of the can is occupied.

40 In order that the sliver piled up in the can a may be compressed and packed into the can 45 satisfactorily, a pair of additional rollers o^1 , o^2 is arranged above the can a , the rollers being parallel to the rollers m^1 and m^2 , while the roller o^1 is outside the roller m^1 and is driven similarly to it and in the same clockwise direction, while the roller o^2 is driven 50 in the same direction as the roller k^2 , that is in a counter-clockwise direction. Thus, when the can is practically filled with sliver, the four rollers, o^1 , k^1 , k^2 , o^2 , act to roll 55 down the sliver and press the same into the can so that as the can reciprocates below the rollers, the sliver is packed firmly into the can.

60 When the can a is full, it is moved to the left and replaced by the empty can e . This may be effected by hand, or, of course, by an automatic doffing mechanism such as that set forth in my co-pending application Serial No. 343,524. In either case, it is desirable 65 when the can a is being removed, that the

70 supply of sliver should be temporarily stopped. For this purpose, a cover or hood p is mounted to swing down into the position shown in chain lines in Figure 2, about an axis q . This may be effected by hand if the cans are shifted by hand, or mechanically if the doffing of the cans is automatic. The effect when the cover p is lowered is to retain the sliver on the delivery plate h and only allow it to fall into the empty can e when the latter has fully arrived in its position to receive the sliver. The cover p is then lifted and the can e continues to be filled as already described.

75 It will be noted that there is a positive gearing connection between the spindle r of the lower delivery roller g^2 and the rollers k^1 and k^2 so that the definite speed relationship can be maintained. This gearing comprises bevel wheels s , a chain t , and the bevel gearing m^1 and m^2 already referred to.

80 It will be appreciated that although the invention has been described in the above example in its application to a carding engine, it can be applied equally well to any textile machine which is intended to deliver sliver 85 to be received in cans.

90 I claim:

95 1. A mechanism for delivering sliver into cans, comprising a pair of rollers arranged above the can with their axes at right angles to the width of the sliver, a driving mechanism connected to said rollers to rotate them in opposite directions so that their upper surfaces move inwardly, and means for delivering sliver to the bite of said rollers near one end thereof at a speed greater than the peripheral speed of said rollers.

100 2. A mechanism for delivering sliver into cans, comprising a pair of rollers arranged above the can with their axes at right angles to the width of the sliver, spaced apart with a gap between them less than the width of the sliver and driven to rotate in opposite directions so that their upper surfaces move inwardly, and means for delivering sliver to the bite of said rollers near one end thereof at a speed greater than the peripheral speed of said rollers.

105 3. A mechanism for delivering sliver into cans, comprising a pair of rollers arranged above the can and frictionally engaging the edges of the sliver, means for rotating them to urge the sliver downwardly, and means for delivering sliver to the bite of said rollers near one end thereof in a direction inclined to the vertical at a speed less than the peripheral speed of said rollers.

110 4. A mechanism for delivering sliver into cans, comprising a pair of rollers arranged above the can and frictionally engaging the edges of the sliver, means for rotating them to urge the sliver downwardly, a pair of sliver-delivery rollers situated above said rollers at one end thereof, engaging the faces 115

of the sliver and means for rotating them at a peripheral speed greater than that of the rollers first mentioned.

5. A mechanism for delivering sliver into cans, comprising a pair of rollers arranged above the can and frictionally engaging the edges of the sliver, means for rotating them to urge the sliver downwardly, a pair of sliver-delivery rollers situated above said rollers at one end thereof, engaging the faces of the sliver, means for rotating them at a peripheral speed greater than that of the rollers first mentioned, a support for the can, and means for reciprocating said can horizontally in a direction transverse to the axes of said rollers first mentioned.

6. A mechanism for delivering sliver into cans, comprising a pair of rollers arranged above the can and frictionally engaging the edges of the sliver, means for rotating them to urge the sliver downwardly, a pair of sliver-delivery rollers situated above said rollers at one end thereof, engaging the faces of the sliver, and positive gearing between said delivery rollers and the rollers first mentioned to cause said delivery rollers to rotate them at a greater peripheral speed than the rollers first mentioned.

7. A mechanism for delivering sliver into cans, consisting of a reciprocating carriage for a can, a pair of rollers with parallel axes at right angles to the direction of motion of said support, said rollers being spaced apart to leave a gap between them, driving means operatively connected to said rollers for rotating them in opposite directions so that their upper surfaces move inwardly, a pair of delivery rollers transversely mounted above the rollers first mentioned at one end thereof and engaging the faces of the sliver, an inclined delivery plate extending between said delivery rollers and the rollers first mentioned, and means for causing the peripheral speed of the delivery rollers to be always greater than that of the rollers first mentioned.

8. A mechanism for delivering sliver into cans, consisting of a reciprocating carriage to support a can, a pair of rollers with parallel axes at right angles to the direction of movement of said carriage, an inclined delivery plate above said rollers, means for feeding sliver over said plate on to said rollers at a speed greater than the peripheral speed of said rollers, a hood movably supported above said plate, mechanism for lowering and raising said hood in driving connection with said rollers, whereby said hood is lowered to nip the sliver on said delivery plate when a can has been filled.

In witness whereof I hereunto subscribe my name this 8th day of February, 1929.

JACK P. MACKIE.
